UNITED STATES PATENT OFFICE.

ARTHUR H. WOLCOTT, OF WINTHROP, MASSACHUSETTS, ASSIGNOR, BY MESNE ASSIGNMENTS,
TO JOHN L. WHITING-J. J. ADAMS CO., OF BOSTON, MASSACHUSETTS, A CORPORATION OF
MAINE.

BRUSH.

No. 909,501.

Specification of Letters Patent.

Patented Jan. 12, 1909.

Application filed May 27, 1908. Serial No. 435,334.

To all whom it may concern:

Be it known that I, ARTHUR H. WOLCOTT, of Winthrop, in the county of Suffolk and State of Massachusetts, have invented 5 certain new and useful Improvements in Brushes, of which the following is a specification.

This invention relates to a brush for applying paint, etc. in which a bunch of 10 bristles or brush filaments is secured at its butt end portion to a handle, the outer portion or flag of the bunch being exposed and flexible.

The invention has for its object to provide simple and effective means for binding or clamping the butt ends of the bristles securely together independently of the handle, and securing the bunch to the handle.

The invention is embodied in a brush in 20 which the end of a bunch of bristles or brush filaments formed by the butts of the bristles, is inserted in a metal cup having a bottom and a flange integral therewith, the flange surrounding the butt end of the bunch and holding the same in a compressed condition which may be caused wholly by the contraction of the cup to force the flange inwardly upon the base of the bunch, or by both the contraction of the cup and the expansion of the said base. In either case the bottom of the cup constitutes a holding member which connects all parts of the base portion of the flange, and confines the latter against deviation from the form imparted by 30 the compression of the cup required to properly confine the bristles, so that the flange can not relax its grip on the bristles, and cannot be distorted or crimped by inward pressure exerted on its outer surface for the purpose of contracting it. A suitable handle is provided on which the bottom of the cup is seated, means being provided for securing the cup to the handle.

Of the accompanying drawings forming 45 a part of this specification, Figure 1 represents a longitudinal section of a brush embodying my invention. Fig. 2 represents a section on line 2—2 of Fig. 1. Figs. 3 and 4 represent perspective views of different forms of the metal cup. Fig. 5 represents a 50 sectional view of the cup before its compression, showing the butt portion of a bunch of bristles inserted therein. Fig. 6 represents a view similar to Fig. 5, showing 55 the cup contracted to bind the bristles. Fig.

7 represents a view similar to Fig. 2, showing the cup contracted and the base of the bristle bunch spread. Fig. 8 is a view similar to Fig. 7 but showing a different form of spreader.

The same letters of reference indicate the same parts in all the figures.

In carrying out my invention, I provide a cup composed of a bottom 12, and an endless flange or wall 13 surrounding the bottom, 65 the whole being formed from metal, by the action of suitable dies, the metal being of substantial thickness so that when the cup is contracted, as hereinafter described, the flange will be practically rigid. The forming dies leave the flange standing at right angles with the bottom, as shown in Figs. 3 and 5. In the cavity of the cup I insert the butt ends of a bunch 14 of bristles or brush filaments. The flange 13 surrounds 70 the bristle butts, and the bottom constitutes a confining member which rigidly connects all parts of the base of the flange, so that it cannot be distorted or caused to deviate from the predetermined form required to 75 enable it to properly engage and confine the base of the bunch of bristles, and hold the same under compression, as hereinafter described. When the confining engagement between the base of the bunch of bristles 80 and the flange is to be effected wholly by the lateral contraction of the cup, as shown in Figs. 1, 2 and 6, I apply inward pressure, by any suitable mechanical appliances, to practically all parts of the external surface 85 of the flange, and to the margin of the bottom of the cup, in such manner as to force all parts of the flange inwardly and reduce the area of the bottom. The flange is thus caused to exert compressive pressure on the 90 portions of the bristles surrounded by it, the bristle butts being thus firmly clamped and secured to the cup. The reduction of the area of the bottom 12, shown by comparing Fig. 5 with Figs. 6, 7 and 8, prevents 95 outward displacement of the contracted flange by the effort of the compressed bristle bunch to expand. The bottom also prevents any distortion, buckling or crimping 100 of the flange by the pressure exerted in contracting it, the bottom acting in this respect as a strut or brace which rigidly supports the base portion of the flange, and enables it to be uniformly and evenly contracted at all 105 points, without being distorted, crimped or 110

buckled, and without deviating from the desired predetermined form. Owing to the presence of the bottom, a greater inward contraction of the flange is permitted without distortion, crimping or buckling, than would otherwise be possible, the contraction of the bottom preserving the contracted shape imparted to the flange. If the flange were an open ferrule or band having no bottom, heavy pressure applied to its outer surface to contract the flange, would result in the distortion or crimping of the flange, so that it would not acquire the desired predetermined form.

15 When the confining engagement between the base of the bunch and the flange is to be effected both by contracting the cup and spreading the base of the bristle bunch, as shown by comparing Figs. 7 and 8 with Fig. 5, the cup may be contracted after the insertion of a spreader 20 into the base of the bristle bunch, the bristles being thus doubly compressed. In this case the bottom acts both to prevent the spreading or outward yielding of the flange to the pressure of the bristles against it, and also to prevent distortion or crimping of the flange by the pressure which contracts it.

The cup may be oblong in form, as shown in Fig. 3, or it may have a circular form, which is intended to be represented by Fig. 4, or it may have an elliptical or any other suitable form.

After the cup has been engaged as described with the bristles, it may be secured in any suitable way to a handle 15, one end of which is preferably formed as a seat 16 for the bottom 12. In Figs. 1 and 2 I show, as the means for holding the cup bottom 40 against said seat, a sheet metal sleeve 17, which is formed to surround the sides of the cup. One of the end portions of the sleeve is suitably secured to the handle, and the other end portion is contracted to form a 45 shoulder 19 engaging the outer edge of the flange, 13.

In Figs. 7 and 8, I show the cup held

against the seat on the handle by the spreader 20 and nails 21 driven through holes in the spreader and in the cup bottom 50 into the handle.

In each of the described embodiments of the invention, the cup constitutes a connecting medium between the bristles and the handle, the bristles being held securely together in an operative bunch independently of the handle, so that the operation of attaching the cup to the handle establishes a connection between the bristles and the handle. 60

I claim:

1. A brush comprising a metal cup having a bottom and a flange integral therewith, and a bunch of bristles or brush filaments, the base of which is surrounded by the flange, the cup including its bottom being compressed on the base of the bristles to hold them in a compressed condition, the said bottom constituting a holding member which rigidly confines the flange against deviation from its predetermined form. 70

2. A brush comprising a bunch of bristles or brush filaments, a metal cup in which the base of the bunch is inserted, said cup having a bottom and a flange integral therewith, the cup including its bottom being compressed on the base of the bunch to hold said base in a compressed condition, the bottom constituting a holding member which confines the flange against deviation from its predetermined form, a handle on which the bottom is seated, and means for securing the cup to the handle. 80

3. A brush comprising a metal cup having a bottom and a flange integral therewith, and a bunch of bristles or brush filaments held in a compressed condition by the flange and said bottom being contracted in area. 85

In testimony whereof I have affixed my signature, in presence of two witnesses.

ARTHUR H. WOLCOTT. [L. S.]
